UNITED STATES PATENT OFFICE.

OLIVER MARGETSON, OF LONDON, ENGLAND.

CYLINDER CONSTRUCTION OF INTERNAL-COMBUSTION ENGINES.

Application filed July 3, 1923. Serial No. 649,813.

To all whom it may concern:

Be it known that I, OLIVER MARGETSON, a subject of the King of Great Britain, and a resident of London, England, have invented 5
a certain new and useful Improvement in the Cylinder Construction of Internal-Combustion Engines, of which the following is a specification.

This invention relates to the cylinder construction of internal combustion engines and has particular reference to engines wherein the jackets of cylinders are under pressure and form part of a steam generating system.

The outer shells of the castings of the 15 cylinders of such engines are subject to pressure and in the event of fracture there would be a danger of steam and water being discharged into the engine room and the object of my invention is to obviate this 20 danger and at the same time strengthen the general structure.

The invention consists broadly in casting the jacketed cylinder and its valve pockets in the usual manner and then shrouding 25 the exposed cylinder wall in a casing of steel held in position by bolts and nuts.

In accordance with the invention I provide the shrouding in parts adapted to fit over the outer wall of the casting the parts 30 meeting at joints which telescope one into the other, or otherwise overlap, studs or bolts passing through abutting flanges and serving to hold the structure together.

The cylinder end covers may be in the 35 form of steel plates or discs or may be continuous with cylindrical extensions which embrace the cylinder ends and interengage with adjacent cylindrical sheaths or shrouds.

By means of the foregoing the cylinder 40 structure as a whole is very much strengthened and all danger of accident through the discharge of hot water or steam is eliminated.

In order that the invention may be clearly 45 understood two embodiments of the same will now be described by aid of the accompanying drawings in which:—

Figure 1 is a vertical section through an 50 internal combustion engine cylinder illustrating one embodiment of this invention.

Figure 2 is a similar view but illustrating another embodiment of the invention.

In the drawings the cylinders are cast 55 with the usual water jackets and water pock-

ets the walls of which are either constituted by or supported by steel casings held in position by nuts and bolts or their equivalent.

Referring now particularly to Figure 1 the design of the cylinder shown comprises 60 a cylinder barrel *a* having a water jacket *b*, a head or cover *c* carrying the usual inlet and exhaust valves, one of which is indicated at *d* which valves are surrounded by water pockets *e*. In this example the steel 65 casings comprise a cover plate *f* which is bolted to the upper part of the cylinder barrel *a* by bolts *g* so as to serve as a closure for the open ends of the water pockets *e*. The water jacket *b* is enclosed at its upper 70 end by a wall *h* cast integral with the cylinder barrel which wall is supported by a steel shrouding or casing *i*. This casing *i* is provided at its upper end with an in-turned flange *j* which rests upon a circumferential surface formed for its reception on the upper part of the cylinder barrel *a*. The lower end of this casing is provided with an outwardly extending circumferential flange which is adapted to oppose a correspondingly shaped flange *k* formed on the adjacent upper part of a further steel casing *l*. This latter casing *l* constitutes the outer wall of the major and lower portion 75 of the water jacket *b* and its upper end is 80 extended as at *m* beyond the flange *k* said extension fitting within the lower end of the upper casing *i* its top edge abutting against the bottom edge of the wall *h*. The two casings *i* and *l* are held together by bolts or 85 the like not shown which engage the opposing flanges of such casings.

In the modified arrangement illustrated in Figure 2 the cover plate *f* and casing *i* which are separate attachments in Figure 1 90 are in this example constituted by a single casing *n* which is flanged at its lower edge as at *o* and bolted to the opposing flange *k* of the casing *l* as in the example first described.

What I claim and desire to secure by Letters Patent is:—

1. A cylinder construction for internal combustion engines in which the outer or exposed walls of the water jackets or pockets are supported or constituted by casings or shrouds of steel.

2. A cylinder construction for internal

combustion engines as in claim 1 in which such steel casings or shrouds are held in position by bolts and nuts or their equivalent.

- 5 3. A cylinder construction for internal combustion engines as in claim 1 wherein the encasing or shrouding of the walls of

the water jackets or pockets is effected by means of a plurality of cast steel members which are secured to the cylinder casting 10 and in some cases to each other by bolts and the like fastening means.

In witness whereof I affix my signature.
OLIVER MARGETSON.
